UNITED STATES PATENT OFFICE.

JOHN WILLS CLOUD, OF LONDON, ENGLAND.

APPARATUS FOR AERIAL MACHINES, NAUTICAL SHIPS, VEHICLES, AND OTHER PURPOSES.

968,127

Specification of Letters Patent. Patented Aug. 23, 1910.

Application filed March 9, 1909. Serial No. 482,366.

To all whom it may concern:

Be it known that I, JOHN WILLS CLOUD, a citizen of the United States of America, and a resident of London, England, have 5 made a new and useful Invention in Improvements Relating to Apparatus for Aerial Machines, Nautical Ships, Vehicles, and other Purposes, of which the following is a specification.

10 This invention relates to the propulsion of vessels for navigating the air and its object is to provide and arrange mechanism of propulsion so that all of the main deflecting forces which are set up by the operation of 15 the engines or motors and by the moving mechanism connected thereto shall at all times be as nearly counterbalanced as may be possible by equal forces of the same nature and similar origin acting in the opposite direction, so that there shall be practically no resultant deflecting forces arising 20 from the mechanism or from its motion at any time, and there remains to be dealt with only its gravity which is balanced by 25 the buoyant effort of the air and the direct propulsive effort.

A vessel navigating the air is in such delicate balance in all directions that its course and its position are very much affected by 30 small disturbing forces. It becomes therefore of essential importance that no unbalanced disturbing forces should be generated by the movements of the mechanism of propulsion, and numerous accidents have 35 recently occurred as a result of such unbalanced deflecting forces being developed.

When reciprocating engines are employed to drive the propelling machinery, the main deflecting forces which are developed and 40 which by this invention I design to counterbalance may be enumerated under the following heads. 1st. Forces arising from the reciprocating masses of the engines. 2nd. Forces arising from the reactions of the 45 rotary forces applied to the cranks. 3rd. Forces arising from the reaction of the gases escaping from the cylinders. 4th. Forces arising from rotary masses when the direction of the axes of rotation is changed. 50 It has already been suggested to balance some of these forces, for example, it has been proposed to arrange the cylinders of multi-cylinder reciprocating engines in particular positions with reference to each other

and to provide balance weights in order that 55 the forces set up by the inertia of the reciprocating parts shall be balanced. It has also been proposed to balance the rotational forces due to the reaction of the effort on the crank pin by utilizing two cylinders located side by side and having their combustion chambers connected, the pistons of the cylinders being connected to separate crank shafts rotating in opposite directions. The 60 fourth set of forces, namely those developed 65 when the angular direction of the crank shaft axis is changed may be balanced by means such as described in application for Letters Patent Serial No. 450364 made on the 26th August 1908. It has never so far 70 as I am aware been proposed to take account of all of these disturbing elements in aeroplane mechanism and to balance the rotating parts, and my present invention consists in 75 so constructing and arranging the engines and the devices to be rotated that all of the disturbing forces above mentioned shall be as nearly as possible approximately counterbalanced.

According to my invention, vessels for 80 navigating the air are characterized by duplicate sets of engines the cylinders of one set having their axes parallel with the corresponding cylinders of the other set. These engines drive parallel crank shafts which 85 are geared together so as to rotate at the same speed but in opposite directions and drive the propeller shafts. The reciprocating parts of the engines are balanced and the pistons of corresponding cylinders driv- 90 ing each shaft are acted upon by similar propelling forces and are arranged to move in similar directions at all times so that no resultant couple will arise from the reactions of the forces exerted on the cranks. 95 The rotary momentum of the various wheels, shafts and propellers rotating in one direction is also made substantially equal to the rotary momentum of the wheels, shafts and propellers rotating in the opposite direction, in order to prevent any resultant 100 deflecting forces being developed when the direction of the axis of rotation of the various parts is changed. By making these arrangements I insure that the whole of the 105 machinery shall be completely balanced under all conditions of operation.

In order that my invention may be

clearly understood I have shown in the accompanying drawings, by way of example, how it may be carried out in practice.

Figure 1 is a plan of the engines and propelling shafts in which four pairs of cylinders are provided for driving the propellers. Fig. 2 is a side elevation. Fig. 3 is a section on the line III—III Fig. 1 drawn to an enlarged scale. Fig. 4 is a skeleton plan showing another arrangement of the propeller shafts and Fig. 5 is an end view of the same.

Referring now to Figs. 1 to 3, one set of engines comprising the cylinders 1, 2, 3, 4 is arranged to drive the shaft 5 and a duplicate set of cylinders 6, 7, 8, 9 is arranged opposite to them driving the parallel shaft 10, the shafts 5 and 10 are geared together by spur wheels 11, 12 so as to rotate at the same speed in opposite directions. The pistons of corresponding cylinders, namely 1 and 6, 2 and 7, 3 and 8, 4 and 9 are arranged so as to exert their driving forces at the same moment, this will be clear from an inspection of Fig. 3 which shows a section of the cylinders 4 and 9, and it will be seen that the pistons 13 and 14 of these cylinders are both at the top of the stroke, and also the combustion chambers of the cylinders are connected together by a passage 15 and have a common inlet valve 16. It will be seen that the reactive force impressed upon one cylinder due to the force exerted upon the crank pin by its piston will be balanced by the reactive effect due to the force exerted on the crank pin by the piston of the corresponding cylinder, consequently there will be no resultant force tending to rotate the engine frame or the frame which carries it; the same will be true of each pair of cylinders and consequently will apply to the entire duplicate set of engines. Considering the cylinders of one set as shown in Fig. 2 it will be seen that the pistons 14, 17 of the extreme cylinders 9, 6, occupy similar positions and the pistons 18, 19 of the two intermediate cylinders 7, 8 occupy also similar positions but at the opposite end of the cylinders, in other words the extreme end cranks are at an angle of 180° with the two intermediate cranks, by this means the reciprocating movements of the pistons and parts connected therewith of all the cylinders will be balanced about a point 20 midway between the two intermediate cranks. The engines in this arrangement are internal combustion engines working upon a four-stroke cycle, such as the well known "Otto" cycle, and the explosions may be arranged to occur in the cylinders in the following order, namely, 6 and 1, 8 and 3, 9 and 4, 7 and 2, by this means an impulse every half revolution of the crank shaft will be obtained.

65 The exhaust ports of the cylinders 1, 2, 3,

4 forming one set lead into a common exhaust pipe 21 and the exhaust ports of the cylinders 6, 7, 8, 9, of the other set lead into a similar exhaust pipe 22, these pipes being symmetrically arranged on each side of the axis of the combined engines and arranged to deliver the exhaust gases in a similar direction so that no resultant couple will arise from the expulsion of such exhaust gases. The exhaust gases can be expelled in other directions than in the fore and aft directions shown, provided that the final exit ports of both sets of cylinders are arranged to force the gases in such directions that no resultant couple is produced by the reactions. 80

The propeller shafts, of which there are two, are located concentrically in the arrangement shown in Figs. 1 to 3, the inner shaft 23 is provided with a spur gear 24 driven from the pinion 25 on the crank shaft 5; said shaft 23 is furnished with a propeller 26; the outer shaft which is, of course, made tubular so as to contain the inner shaft, is indicated at 27 and is provided with a spur gear 28 which engages 90 with a pinion 29 on the crank shaft 10. The propeller carried by the tubular shaft 27 is indicated at 30. As the two propeller shafts are rotated in opposite directions, the pitch of the one propeller must be opposite to that of the other propeller as shown. The thrust of the inner propeller shaft 23 in the forward direction is taken direct by the bearing 31 and the thrust of the outer tubular shaft 27 is taken by the same bearing being transmitted through the hub of the spur wheel 24. The rearward thrust of the two shafts is taken by the bearing 32, that of the shaft 23 being transmitted from the hub of the wheel 24 through the flange 33 of the shaft 105 27 and thence through the hub of the wheel 28. The rotary momentum of the crank shaft 5, gear wheel 25 and other parts rotating co-axially therewith is made equal to the rotary momentum of the crank shaft 10, gear wheel 29 and parts rotating co-axially with said shaft, also the rotary momentum of the propeller 26, shaft 23 and spur wheel 24 is made equal to the rotary momentum of the propeller 30, tubular shaft 27 and 110 spur wheel 28, by this means since the shafts 5 and 10 rotate in opposite directions at the same speed and the propellers 26 and 30 also rotate in opposite directions at the same speed, there will be no resultant forces set 115 up when the direction of the axis of the parts is changed.

In place of mounting the two propellers on co-axial shafts I may mount them directly on the crank shafts 5 and 10 provided these are not located too near together, or I may gear the crank shafts 5 and 10 to two propeller shafts arranged symmetrically on either side of the center line as shown in Figs. 4 and 5 where the propeller 130

shafts 34, 35 are connected by gear chains 36, 37 to the crank shafts 5 and 10 respectively. The propeller shafts will in this case be similar in all respects but will be arranged

- 5 to rotate in opposite directions so as to avoid the development of any resultant force when the direction of the axis of the machine is changed. The framework supporting the propeller shafts in this case should be made 10 as rigid as possible so as to prevent undue vibration.

Where it is not necessary to have an impulse every half revolution, or where the engines are of such a type as to obtain this 15 effect with single cylinders as is the case with ordinary double acting steam engines, I may employ two cylinders arranged as shown in Fig. 3, for example, in place of the 8 cylinders hereinbefore described. In 20 such a case the reciprocating parts should each be separately balanced by suitable balance weights arranged opposite the cranks, but it may be observed that these balance weights should be symmetrically located on 25 each side of the center line of the cylinder in order to avoid any unbalancing on an axis at right angles to the crank shaft. Any known form of engine may be employed for the purpose of my invention provided the 30 principles above enunciated are adhered to.

I have already said that some of the deflecting forces above referred to have long been counterbalanced but I am not aware that any construction has heretofore been 35 proposed for this purpose which combines the counterbalancing of all these forces in the way which I describe and which is of primary importance in mechanism for the propulsion of vehicles for navigating the air.

40 I claim as my invention:

1. In a vessel for navigating the air, the combination of a reciprocating engine the reciprocating parts of which are balanced, a shaft driven thereby, a second reciprocating 45 engine similar to the first mentioned engine, having the center line of its cylinder parallel with that of the cylinder of the first engine, and with its piston arranged to move in similar directions at the same time 50 as the piston of the first engine, a shaft driven by said second engine parallel with the shaft of the first engine, gearing connecting the engine shafts for insuring their rotation at the same speed in opposite directions, and propellers rotated by said shafts.

2. In a vessel for navigating the air, the combination of a reciprocating engine the reciprocating parts of which are balanced, a shaft driven by said engine, a second engine 60 similar to the first-mentioned engine, a shaft driven by said second engine parallel with the shaft of the first engine, means whereby the pistons driving each shaft are acted upon by similar propelling forces and are 65 forced to move in similar directions at the

same time, gearing connecting the engine shafts for insuring their rotation at the same speed in opposite directions and propellers rotated by said shafts.

3. In a vessel for navigating the air, the 70 combination of a reciprocating engine the reciprocating parts of which are balanced, a shaft driven thereby, a second reciprocating engine similar to the first-mentioned engine, a shaft driven by said second engine 75 parallel with the shaft of the first-mentioned engine, gearing connecting the engine shafts for insuring their rotation at the same speed in opposite directions, propeller shafts parallel with the engine shafts, and 80 gearing connecting the propeller shafts severally with the engine shafts.

4. In a vessel for navigating the air the combination of a multi-cylinder reciprocating engine the reciprocating parts of which 85 are balanced, a shaft driven thereby, a second reciprocating engine similar to and having its cylinders arranged opposite the cylinders of the first mentioned engine, a shaft driven by said second engine parallel to the 90 shaft of the first engine, means whereby the pistons of one engine are acted upon by similar propelling forces and are forced to move in similar directions at the same time as the corresponding pistons of the other 95 engine, gearing connecting the engine shafts for insuring their rotation at the same speed in opposite directions and propellers rotated by said shafts.

5. In a vessel for navigating the air, the 100 combination of a multi-cylinder reciprocating engine the reciprocating parts of which balance each other, a shaft driven thereby, a second reciprocating engine similar to the first-mentioned engine, a shaft driven by 105 said second engine parallel with the shaft of the first engine, gearing connecting the engine shafts for insuring their rotation at the same speed in opposite directions, and propeller shafts rotatably connected with 110 the engine shafts, the rotary momentum of the parts rotating in one direction being equal to the rotary momentum of the parts rotating in the other direction.

6. In a vessel for navigating the air, the 115 combination of a reciprocating engine the reciprocating parts of which are balanced, a shaft driven thereby, a second reciprocating engine similar to the first-mentioned engine, exhaust pipes for said engines arranged so that the movement of the exhaust gases from one engine balances the movement of the exhaust gases from the other engine, a shaft driven by the second engine 120 parallel with the shaft of the first engine, gearing connecting the engine shafts for insuring their rotation in opposite directions, and propellers rotated by said shafts.

7. In a vessel for navigating the air, the 130 combination of a reciprocating engine the

reciprocating parts of which are balanced, a shaft driven thereby, a second reciprocating engine similar to the first-mentioned engine, exhaust pipes for said engines symmetrically arranged on each side of the axis of the combined engines and delivering the exhaust gases in the same direction, a shaft driven by the second engine parallel with the shaft of the first engine, gearing connecting the engine shafts for insuring their rotation in opposite directions, and propellers rotated by said shafts.

8. In a vessel for navigating the air, the combination of a reciprocating engine the reciprocating parts of which are balanced, a shaft driven thereby, a second reciprocating engine similar to the first-mentioned engine, exhaust pipes for said engines arranged so that the movement of the exhaust gases from one engine balances the movement of the exhaust gases from the other engine, a shaft driven by said second engine parallel with the shaft of the first engine, means whereby the pistons driving each shaft are acted upon by similar propelling forces and are forced to move in similar directions at the same time, gearing connecting the engine shafts for insuring their rotation in opposite directions, and propellers rotated by said shafts.

9. In a vessel for navigating the air, the combination of a reciprocating engine the reciprocating parts of which are balanced, a shaft driven thereby, a second reciprocating engine similar to the first-mentioned engine, exhaust pipes for said engines arranged so that the movement of the exhaust gases from one engine balances the movement of the exhaust gases from the other engine, a shaft driven by said second engine parallel with the shaft of the first engine, means whereby the pistons driving each shaft are acted upon by similar propelling forces and are forced to move in similar directions at the same time, gearing connecting the engine shafts for insuring their rotation in opposite directions, and propellers rotated by said shafts, the rotary momentum of the parts rotating in one direction being equal to the rotary momentum of the parts rotating in the other direction.

10. In a vessel for navigating the air, the combination of a reciprocating engine the reciprocating parts of which are balanced, a shaft driven thereby, a second reciprocating engine similar to the first-mentioned engine, a shaft driven by said second engine parallel with the shaft of the first-mentioned engine, gearing connecting the engine shafts for insuring their rotation at the same speed in opposite directions, co-axial propeller shafts parallel with the engine shafts, and gearing connecting the propeller shafts severally with the engine shafts.

11. In a vessel for navigating the air, the

combination of a reciprocating engine the reciprocating parts of which are balanced, a shaft driven thereby, a second reciprocating engine similar to the first-mentioned engine, a shaft driven by said second engine parallel with the shaft of the first engine, gearing located at one end of the engine shafts and connecting the same, to insure their rotation in opposite directions, propeller shafts and gearing rotated at the other end of the engine shafts connecting them severally to the propeller shafts so that the propeller shafts rotate at the same speed in opposite directions.

12. In a vessel for navigating the air, the combination of a multi-cylinder reciprocating engine the reciprocating parts of which are arranged to balance each other, a shaft driven thereby, a second engine similar to the first-mentioned engine, a shaft driven by said second engine parallel with the shaft of the first engine, exhaust pipes for said engines arranged so that the movement of the exhaust gases from one engine balances the movement of the exhaust gases from the other engine, means whereby the pistons driving each shaft are acted upon by similar propelling forces and are forced to move in similar directions at the same time, gearing connecting the engine shafts for insuring their rotation in opposite directions and propellers rotated by said shafts, the rotary momentum of the parts rotating in one direction being equal to the rotary momentum of the parts rotating in the other direction.

13. In a vessel for navigating the air, the combination of a multi-cylinder reciprocating engine the reciprocating parts of which are arranged to balance each other, a shaft driven thereby, a second engine similar to the first-mentioned engine, a shaft driven by said second engine parallel with the shaft of the first engine, exhaust pipes for said engines symmetrically arranged on each side of the axis of the combined engines, and delivering the exhaust gases in the same direction, means whereby the pistons driving each shaft are acted upon by similar propelling forces and are forced to move in similar directions at the same time, gearing connecting the engine shafts for insuring their rotation in opposite directions, and propellers rotated by said shafts, the rotary momentum of the parts rotating in one direction being equal to the rotary momentum of the parts rotating in the other direction.

In testimony whereof, I have hereunto subscribed my name this 24th day of February 1909.

JOHN WILLS CLOUD.
